FRANCIS J. CLAMER, OF PHILADELPHIA, PENNSYLVANIA.

Design No. 2,671, dated June 11, 1867.

DESIGN FOR A NAPKIN-RING.

The Schedule referred to in these Letters Patent and making part of the same.

TO ALL WHOM IT MAY CONCERN:

Be it known that I, FRANCIS J. CLAMER, of the city of Philadelphia, in the State of Pennsylvania, have invented or produced a new and original ornamental Design for a Napkin-Ring; and I do hereby declare that the following is a full, clear, and exact description of the same, reference being had to the accompanying drawing, making a part of this specification, and to the letters of reference marked thereon.

This design consists in giving to a napkin-ring an oval or elliptical form in its circumference, with a broad oval-like face for its upper side, and having in the centre of its said face-side a tablet ornamented with a photographic picture on its face.

Referring to the drawing, A is the oval or elliptical ring, and a' the ornamented tablet on the face-side of the ring A.

What I claim as my invention or production, and desire to secure by Letters Patent, is—

The design herein described and shown for a napkin-ring.

F. J. CLAMER.
